UNITED STATES PATENT OFFICE

BO-GABRIEL MONTGOMERY, OF DJURSHOLM, SWEDEN

RAZOR-SHARPENING DEVICE

Application filed August 4, 1927, Serial No. 210,658, and in Sweden July 9, 1926.

This invention relates to blade conditioning devices such as knife or razor sharpening or honing devices.

According to this invention the device comprises a stationary blade holder and a strop or hone adapted to be drawn to and fro over the edge of the blade which is automatically reversed through the rocking of the holder as the direction of movement of the strop or hone is reversed.

The invention is particularly applicable to devices which comprise a case or box having a sliding lid on which is carried a strop or hone against which the edge of a blade mounted on a rotatable axis in the box, is pressed as the lid is moved to and fro along the box, the blade being turned automatically in the required direction as the sliding movement of the lid is reversed.

Further, according to the present invention the lid of the box is so constructed that when it is slid to and fro along the top of the box to draw the strop or hone in a direction from the back of the blade towards the edge which is being sharpened in whichever direction the lid is being moved, it also causes the blade to be moved, zig-zag across the strop or hone.

Conveniently the to and fro or zig-zag movement is imparted to the blade holder and therefore to the blade by a cam-path arranged alongside the strop or hone on the lid of the box.

Referring to the accompanying drawings:

Fig. 1 is a longitudinal sectional elevation of a device constructed in accordance with or embodying the present invention;

Fig. 2 is a cross sectional elevation of the device shown in Fig. 1;

Fig. 3 is a plan of the device shown in Figs. 1 and 2 but with the lid or cover removed.

Fig. 4 is an inverted plan of the lid or cover separately and

Fig. 5 is an inverted plan of a modified construction of lid.

Fig. 6 is a part sectional elevation showing a further modification of the invention.

In the embodiment illustrated in Figs. 1

to 4 the device is constructed so that when the strop is drawn over the edge of the blade the latter has imparted to it a zig-zag movement across the strop or hone.

Mounted in the body of the box or case 55 A near one end thereof is an axle B the ends of which project through the opposite sides of the case. Mounted on the axle B is a holder C for a razor blade D. Toothed pinions E are secured to the axle B at each end 60 of the blade holder C.

Mounted upon posts F secured to the bottom of the case A is an axle F¹ upon which are carried toothed sectors or discs G which gear with the pinions E.

The posts F may be carried on springs or spring supports.

The lid A¹ of the box or case A is furnished on its inner or under surface with the strop or hone H and has rims A² the 70 lower edges of which are inturned to embrace flanges A³ on the upper edges of the side walls of the case.

When the lid is slid along the top of the box from right to left as shown in Fig. 1 the strop or hone H presses against the plain or untoothed portions of the discs G and causes them to rotate a certain distance and they in turn rotate the pinions E and so turn the holder C to bring the edge of one side of the blade D into contact with the holder.

The number and position of the teeth on the discs G are so arranged that the rotation of the pinions is stopped when the edge of the blade is brought into proper contact with the strop or hone. When the lid has been moved to the extreme of its travel the sliding motion of the lid is reversed, the discs G will be rotated in the opposite direction to rotate the pinions E and reverse the position of the bladeholder and thus bring the opposite side of the blade D into contact with the strop or hone.

In order to prevent injury to the blade by the premature rotation of the discs G and pinions E, when the lid is being placed in position, the strop or hone H is cut away at the parts h as shown in Fig. 4.

Thus far described the strop will simply 100

be drawn over the edges of the blade as the latter is pressed against it, but as already stated, in the arrangement illustrated in Figs. 1 to 4 a zig-zag or to and fro movement is given to the blade in a direction across the strop.

This zig-zag movement is imparted by cam surfaces J J^1 formed on the faces of the inturned edges of the lid A^1 (see Figs. 10 2 and 4).

The cam surfaces J J^1 are so arranged that the crests of, say, the cam surface J are opposite the hollows of the cam surface J^1 .

15 These cam surfaces bear against the ends of the axle B so they impart an endwise movement to this axle and hence to the blade holder C as the lid is moved to and fro along the box.

20 In place of being moved positively to and from by two cam surfaces, the axle may be moved in one direction by a cam surface and in the other direction by a spring acting preferably against the end of one of the 25 toothed pinions on the shaft of the blade carrier.

When the zig-zag or to and fro movement of the carrier is not desired the cams J J^1 are omitted and the lid is formed with plane 30 edges as shown in Fig. 5. In this case also the ends of the shafts of the blade carrier may be shortened.

In order to prevent the lid from being accidentally withdrawn there is provided on 35 one or both walls of the box a spring-controlled stop K which is adapted to be engaged by a pin or shoulder A^4 on the lid.

The device is primarily intended for use 40 with blades for safety razors, but it is to be understood that it is equally suitable for other blades.

Further the invention may be applied to a safety razor without removing the blade from the razor as shown in Fig. 6. In this 45 instance the razor comprises a handle 10 having the usual blade support and guard 11, the latter having upturned lugs 12 at its ends for engaging the ends of the blade on its cutting edge in the known manner.

50 The blade support is fitted with a pivoted fork 13 in which a rotatable axle 14 carrying a clip 15 for holding the blade 16 is mounted. One end of the axle is fitted with a pinion 17. The shaving position of the blade is shown in dotted lines. When it is desired to strop the blade, the razor is placed in the case with the ends of the axle 14 resting in slots 20 in the case, one only being 55 shown, and the fork 13 is raised to bring the pinion 17 into engagement with a single toothed disc G . Two discs G are unnecessary in this arrangement. A pin 18 may be provided for limiting the movement of the 60 fork in the stropping position. The fork is 65

held in the shaving position by friction on the pivot 19.

Although the invention has been described as particularly applicable to devices comprising a box having a sliding lid, it may be embodied in other forms of devices in which the blade-holder is mounted upon a stationary or flexible support and the sliding hone or strop-carrying device is mounted to move to and fro relatively to the holder and also to 75 impart a zig-zag movement to the blade-carrier and effect the reversal of the blade at the proper time.

Having thus described the nature of my 80 said invention and the best means I know of carrying the same into practical effect, I claim:—

1. In a blade conditioning device and in combination, a casing, a sliding lid, blade conditioning means on the lid, a rotatable 85 axis in the casing, a reversible blade holder on the axis, pinions on the axis, toothed discs gearing with the pinions rotatably mounted in the casing, and a cam surface on the sliding lid adapted to move the blade holder to and fro across the blade conditioning means as the lid is moved.

2. In a blade conditioning device for safety 90 razor blades and in combination, a box, a sliding lid for completely closing the box, 95 blade conditioning means on the inside of the lid, a rotatable axle in the box, two pinions on the axle, a blade holder on the axle and two toothed discs rotatably mounted in the box and engaging the pinions on the axle, 100 said discs being rotated by the friction of the sliding lid to bring a blade in the blade holder into contact with the blade conditioning means on the lid.

3. In a blade conditioning device for safety 105 razor blades and in combination, a box, a sliding lid for completely closing the box, blade conditioning means on the inside of the lid, a rotatable axle in the box, a reversible 110 blade holder on the axle, and means on the inside of the sliding lid adapted to make contact with the ends of the rotatable axle for giving the blade holder a to and fro movement at right angles to the longitudinal sliding movement of the lid.

4. In a blade conditioning device for safety 115 razor blades and in combination, a box, a safety razor in the box, a pivoted blade holder on the razor, a sliding lid for completely closing the box, blade conditioning 120 means on the inside of the lid, gearing between the blade holder and the lid for bringing the edges of the blade into contact with the blade conditioning means on the lid.

5. A blade conditioning device for safety 125 razor blades comprising a box holding a safety razor complete with blade and having a sliding lid carrying blade conditioning means on the inside thereof, a pivoted blade holder on the razor, toothed gearing between 130

the blade holder and the lid so that when the lid is moved the blade edge is brought into contact with the conditioning means on the lid and mechanism on the lid for moving the blade holder to and fro across the path of the conditioning means.

In testimony whereof I have signed my name to this specification.

BO-GABRIEL MONTGOMERY.
